US0D1045850S

(12) **United States Design Patent** (10) **Patent No.:** **US D1,045,850 S**
(45) **Date of Patent:** **** Oct. 8, 2024**

(54) **MOBILE HARD DRIVE**

(71) Applicant: **GUANGDONG GOPOD GROUP HOLDING CO., LTD.**, Shenzhen (CN)

(72) Inventor: **Zhuowen Liao**, Shenzhen (CN)

(73) Assignee: **GUANGDONG GOPOD GROUP HOLDING CO., LTD.**, Shenzhen (CN)

(**) Term: **15 Years**

(21) Appl. No.: **29/873,204**

(22) Filed: **Mar. 28, 2023**

(30) **Foreign Application Priority Data**

Dec. 8, 2022 (CN) 202230822883.X

(51) **LOC (14) Cl.** **14-02**

(57) **CLAIM**

The ornamental design for a mobile hard drive, as shown and described.

DESCRIPTION

FIG. 1 is a front, right and bottom perspective view of a mobile hard drive showing my new design;

FIG. 2 is a rear, left and top perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines in the figures illustrate portions of the mobile hard drive that form no part of the claimed design.

1 Claim, 8 Drawing Sheets
